(57) **CLAIM**

The ornamental design for a laboratory instrument, as shown and described.

DESCRIPTION

FIG. 1 a front view of a first embodiment of a laboratory instrument.

FIG. 2 is a front view of a second embodiment of a laboratory instrument.

FIG. 3 is a left side view of the laboratory instrument of FIG. 1.

FIG. 4 is a left side view of the laboratory instrument of FIG. 2.

FIG. 5 is a rear view of the laboratory instrument of FIG. 1.

FIG. 6 is a rear view of the laboratory instrument of FIG. 2.

FIG. 7 is a right side view of the laboratory instrument of FIG. 1.

FIG. 8 is a right side view of the laboratory instrument of FIG. 2.

FIG. 9 is a top plan view of the laboratory instrument of FIG. 1.

FIG. 10 is a top plan view of the laboratory instrument of FIG. 2.

FIG. 11 is a bottom plan view of the laboratory instrument of FIG. 1.

FIG. 12 is a bottom plan view of the laboratory instrument of FIG. 2.

FIG. 13 is a perspective view of the laboratory instrument of FIG. 1; and,

FIG. 14 is a perspective view of the laboratory instrument of FIG. 2.

The broken lines show portions of the laboratory instrument that form no part of the claimed design.

The broken line rectangular shape shown within the solid line display panel depicts a portion of the laboratory instrument that forms no part of the claimed design, all other
